Inventor:
Charles J. Sykes
By G. A. Gray Atty

UNITED STATES PATENT OFFICE.

CHARLES J. SYKES, OF CHICAGO, ILLINOIS.

SAVINGS BANK.

Application filed November 24, 1924. Serial No. 751,794.

To all whom it may concern:

Be it known that I, CHARLES J. SYKES, a citizen of the United States, residing at Chicago, in the county of Cook and the State of Illinois, have invented a certain new and useful Improvement in Savings Banks, of which the following is a full, clear, concise, and exact description.

My invention relates to savings banks. 10 The bank of my invention includes a container having a coin slot, a coin receiver removably received within said container and having a coin slot that is in register with the aforesaid coin slot when the receiver is 15 within the container.

In the preferred embodiment of the invention, all walls of the container except the back wall are rigid and the coin receiver is inexpensively made of sheet metal, being 20 virtually a cheap tin can that is sufficiently springy to be pressed inwardly against its resilience by the container to promote the assembly of the receiver and container. The container desirably has a rib formation 25 where it presses against the receiver to localize and thereby make more positive the inward pressure exerted by the container upon the receiver. The interior of the container is desirably extended at its base on both 30 sides of the coin receiver to afford access for the thumb and finger to facilitate removal of the receiver. A tongue is also provided upon one of the elements of the bank, preferably the back wall portion of the container, to further hold said elements together. This container back wall is desirably made of sheet spring metal from which 35 the tongue is struck, this back wall being outwardly bulged in disengaging the tongue 40 from the receiver.

In exploiting the use of the bank, the cheap coin receivers may be supplied, without cost, by drug stores, grocery stores, department stores, etc. to prospective savers 45 who are invited to present the receivers, when sufficiently filled, to designated banks who supply the containers and, usually, additional fillers after accepting the contents of the receivers for the accounts of the 50 savers. The containers are made decorative and otherwise attractive to make the possession thereof desirable. The device of my invention is thus very useful in promoting thrift.

The invention will be more fully explained in connection with the accompanying drawing in which Fig. 1 is a front view, partially in section, showing one embodiment of the invention; Fig. 2 is a sectional view on line 2-2 of Fig. 1; Fig. 3 is a sectional view on line 3-3 of Fig. 1; Fig. 4 is a bottom view of the complete bank; and Fig. 5 is a perspective view of the coin receiver.

The container desirably has a body portion 1 formed of cast metal and furnishing rigid top, front and side walls thereof, the bottom of this body portion being shaped to constitute a supporting base. The back wall 2 of the container is preferably a thin sheet of spring metal which is applied to the body portion of the container by means of screws 3. The container is open at its bottom for the reception of the coin receiver 4 which is desirably made of very thin springy sheet metal, the receiver being of any suitable construction. As illustrated, the end walls 5 and 6 of the receiver have outwardly extending U-shaped marginal portions 7 to receive the edges of the receiver side wall 8, this wall being made continuous by means of the usual form of joint 9 which is common to tin can construction. The receiver is preferably of flat shape with rounded sides, as illustrated. The top wall of the container is formed with a coin slot 10 and the top wall of the removable receiver is formed with a coin slot 11. The two coin slots are adjacent and in register when the coin receiver has been fully inserted within the container so that any coin fully inserted within the slot 10 will find entry into the receiver. These coin slots are in line with the line of movement of the receiver into and out of the container. The rigid front wall of the container is constructed with inner ribs 12 which press inwardly against the adjacent flat side wall of the receiver, which, owing to its resilience, yields sufficiently to effect holding engagement between the receiver and container. The resilient back wall 2 of the container is sufficiently close to the container front wall as to require the back wall to be slightly outwardly pressed and bulged against its resilience, whereby the assembly of the container and receiver is further promoted. The back wall of the container is formed at

its bottom edge with a tongue extension 13 which is adjusted, by outwardly pressing the container back wall 2, to permit the passage of the receiver, the tongue thereafter underlying the receiver when the receiver has been fully inserted. The retention of the receiver within the container is thus further assured. The major portion of the space within the container conforms in shape and size to the receiver so that the two coin slots are bound to register when the receiver is fully placed within the container. The interior of the container, at the base thereof, is extended on both sides of the coin receiver, as illustrated in Fig. 3, to afford access for the thumb and finger to facilitate the removal of the receiver which may be effected as the back wall 2 of the container is flexed sufficiently outward to clear the tongue from the adjacent portion of the contiguous part of the receiver bottom 6, to enable the receiver to pass the tongue as the receiver is being withdrawn.

The container is of any suitable configuration and design, it being preferable to make the container attractive in appearance to invite its location in a conspicuous place while in the possession of the saver, to encourage the use of the bank.

Changes may be made without departing from my invention.

Having thus described my invention, I claim:

1. In a savings bank, the combination with a container having a coin slot; of a coin receiver removably received within said container and having a coin slot that is in register with the aforesaid coin slot when the receiver is within the container, one of the aforesaid elements having a spring wall portion that presses upon the other element to promote the assembly of both elements; and a tongue upon one of the aforesaid elements engaging the other element to further hold said elements in assembly.

2. In a savings bank, the combination with a container having a supporting base end and a coin slot; of a coin receiver removably received within said container and having a coin slot that is in register with the aforesaid coin slot when the receiver is within the container, one of the aforesaid elements having a spring wall portion that presses upon the other element to promote the assembly of both elements, the interior of the container being extended at its base on both sides of the coin receiver to afford access for the thumb and finger to facilitate removal of the coin receiver.

3. In a savings bank, the combination with a container having a rigid wall portion; of a coin receiver removably received within the container and formed of spring sheet material pressing against the container to hold the receiver within the con-

tainer, said elements having coin slots that register when said elements are fully assembled, the interior of the container being extended at its base on both sides of the coin receiver to afford access for the thumb and finger to facilitate the removal of the coin receiver.

4. In a savings bank, the combination with a container having a rigid wall portion; of a coin receiver removably received within the container and formed of spring sheet material pressing against the container to hold the receiver within the container, said elements having coin slots that register when said elements are fully assembled; and a tongue upon one of the aforesaid elements engaging the other element to further hold said elements in assembly, the interior of the container being extended at its base on both sides of the coin receiver to afford access for the thumb and finger to facilitate removal of the coin receiver.

5. In a savings bank, the combination with a container having a rigid wall portion provided with an internal rib formation; of a coin receiver removably received within the container and formed of spring sheet material pressing against said rib formation to hold the receiver within the container, said elements having coin slots that register when said elements are fully assembled.

6. In a savings bank, the combination with a container having a rigid wall portion provided with an internal rib formation; of a coin receiver removably received within the container and formed of spring sheet material pressing against said rib formation to hold the receiver within the container, said elements having coin slots that register when said elements are fully assembled; and a tongue upon one of the aforesaid elements engaging the other element to further hold said elements in assembly.

7. In a savings bank, the combination with a container having a rigid wall portion provided with an internal rib formation; of a coin receiver removably received within the container and formed of spring sheet material pressing against said rib formation to hold the receiver within the container, said elements having coin slots that register when said elements are fully assembled, the interior of the container being extended at its base on both sides of the coin receiver to afford access for the thumb and finger to facilitate removal of the coin receiver.

8. In a savings bank, the combination with a container having a rigid wall portion provided with an internal rib formation; of a coin receiver removably received within the container and formed of spring sheet material pressing against said rib for-

mation to hold the receiver within the container, said elements having coin slots that register when said elements are fully assembled; and a tongue upon one of the ⁵ aforesaid elements engaging the other element to further hold said elements in assembly the interior of the container being

extended at its base on both sides of the coin receiver to afford access for the thumb and finger to facilitate removal of the coin ¹⁰ receiver.

In witness whereof, I hereunto subscribe my name.

CHARLES J. SYKES.
